WO WO 2008/030999 3/2008

Primary Examiner — John Windmuller*Assistant Examiner* — Steven Czyz(74) *Attorney, Agent, or Firm* — Cook Alex Ltd.(57) **CLAIM**

The ornamental design for a catheter package assembly, as shown and described.

DESCRIPTION

FIG. 1 is a perspective view of a catheter package assembly showing our new design.

FIG. 2 is a right side elevational view of the catheter package assembly of FIG. 1.

FIG. 3 is a left side elevational view of the catheter package assembly of FIG. 1.

FIG. 4 is a rear elevational view of the catheter package assembly of FIG. 1.

FIG. 5 is a front elevational view of the catheter package assembly of FIG. 1.

FIG. 6 is a top plan view of the catheter package assembly of FIG. 1; and,

FIG. 7 is a bottom plan view of the catheter package assembly of FIG. 1.

The broken lines depict portions of the article that form no part of the claimed design.
